UNITED STATES PATENT OFFICE

NILS OSKAR WILLINDER, OF JAMSERUM, SWEDEN

DATE INDICATING OR REGISTERING APPARATUS

Application filed July 13, 1931, Serial No. 550,519, and in Sweden July 16, 1930.

This invention relates to date indicating or registering apparatus, which may be used as a calendar clock or a date stamp and has for its object to provide an apparatus of this kind which shall be simple in construction and efficient in operation.

In accordance with the invention date indicating or registering apparatus is provided which comprises day, month and year advancing wheels, adapted to be rotated in a known manner and independently of one another, and a driving member, which is so arranged in relation to these wheels that it advances the day advancing wheel one step per day, adjusts the month advancing wheel to a new month at the end of the month and also adjusts the year advancing wheel to a new year at the end of the year, the month advancing wheel being provided with twelve notches corresponding to the number of months in a year, and of different depths according to the number of days in the corresponding months, and an advancing pin, which is connected with the said driving member and serves to advance the month advancing wheel and which is controlled by a deflecting lever extended in front of the month advancing wheel and a cam path which is arranged to adjust itself according to the depth of the notches in the month advancing wheel, in such a way that, when the day advancing wheel is advanced by the driving member, the advancing pin is prevented from engaging with the month advancing wheel by the deflecting lever until the end of the month and only at the end of the month, when a stop provided on the day advancing wheel moves the deflecting lever and accordingly adjusts the cam path, which serves as a guide for the advancing pin, can the latter come into engagement with the month advancing wheel by passing sooner or later under the deflecting lever.

The accompanying drawings illustrate by way of example a constructional form of the invention. Figure 1 is a plan view of the complete apparatus. Figure 2 is a vertical section on the line A—A of Figure 1, with the discs, which bear the numerals representing the days, months and years, omitted, in

order that the remaining members may be more clearly seen. Figure 3 is a section on the same line as Figure 2, but showing certain members in different positions. Figure 4 is a vertical section on the line B—B of Figure 1, showing some members in other positions. Figures 5 and 6 are views of details of the apparatus.

Referring now to the drawings the clock mechanism itself, which drives the date registering apparatus with a calendar clock, is omitted from the drawings. The date registering apparatus itself comprises a frame consisting of two plates 1, 1^a connected with each other by means of spacing-bolts, a driving member 2, rotatable about a fixed axis 2^a being located between the two plates, this driving member being actuated by the clock mechanism, a pin for example secured to the hour wheel of the clock mechanism being arranged to come into contact once daily with a projection 3 on the driving member 2, the driving member being oscillated thereby. The latter carries a pawl member 4 which when an oscillation of the member 2 takes place under the action of the pin on the hour wheel of the clock mechanism engages with a toothed day advancing wheel 5, which is provided with thirty-one teeth, and then moves this wheel round by one tooth. The teeth of the wheel 5 correspond to the days of the months in which there are thirty-one days. The driving member 2 is under the influence of a leaf-spring 6, which after each oscillation of the member 2 returns it to its initial position.

The day advancing wheel 5 is rigidly connected to a sleeve 7 which is rotatably located on a shaft 8 mounted between the two plates 1, 1^a and carries a day-disc 9 (Figure 1) with the day numbers 1, 2, 3 . . . 31 marked on the periphery thereof. To prevent an accidental adjustment of the day advancing wheel 5, a lever 10 is provided with a locking pin 11 adapted to engage with the teeth of the wheel, this lever, in the position of rest of the driving member 2 (Figure 3), being in turn locked by a pin 12 located on the driving member, the pin 100

12 being adapted to engage with a notch 13 (Figure 4) in the locking lever 10.

The driving member 2 is further provided with a finger 14, which is rotatably connected thereto (as may best be seen from Figures 1 and 4), and the object of which is, as is described in more detail hereinafter, on one hand by the cooperation of its front edge 14' and a transverse pin 20 provided on the day-advancing wheel 5 to advance the day-advancing wheel 5 by as many more teeth as the difference between the number of days in the corresponding month and thirty-one days, at the end of the months having less than thirty-one days, by the same oscillation of the driving member 2 as that by which the pawl 4 ordinarily advances the day advancing wheel 5 by one single tooth and on the other hand by means of a transverse pin 15 secured to the finger 14, at the end of each month advances a month advancing wheel 16 and at the end of the year advances a year advancing wheel 17 also. The month advancing wheel 16 has in its periphery twelve notches corresponding to the number of months in a year. The year advancing wheel 17 is here shown by way of example as having twelve notches corresponding to twelve years, the maximum period of time the calendar clock here illustrated will run.

When the clock mechanism is in operation and the driving member 2 advances the day-advancing wheel 5, the pin 15 of the finger 14 slides on to a cam path 18, which is formed by the arcuate upper edge of a rotatable deflecting lever 19, and is thereby prevented from coming into engagement with the month advancing wheel 16 provided with twelve notches, except when the said month advancing wheel is to be adjusted to a new month, in which case the transverse pin 20 of the day advancing wheel 5 raises the lever 19 by its edge 19' in such a way that the pin 15 of the finger 14 is then permitted to engage with a notch in the month advancing wheel 16, in order to advance the latter by one notch. As will be seen from the drawings, the cam path 18 is outside the circumference of the month advancing wheel 16. The month advancing wheel 16 is rigidly connected with a sleeve 21, which is loosely mounted on the sleeve 7 connected with the day advancing wheel 5, so that the two sleeves can rotate independently of one another. The sleeve 21 carries a month-disc 22 (Figure 1) with the numbers 1, 2 . . . 12 corresponding to the months marked on the periphery thereof.

The depth of each of the twelve notches of the month advancing wheel 16 corresponds to the number of days in the corresponding month, in such a way that the notches for months with thirty days are deeper than the notches for months with

thirty-one days, while the notch for the month of February is still deeper than those for months with thirty days. For the sake of clearness, the deepest notch, i. e. the one for the month of February, bears the reference numeral 23, the four next-deepest notches, which are all equally deep and correspond to the months with thirty days, i. e. April, June, September and November, are numbered 24, while the shallowest notches, seven in number, which correspond to the months with thirty-one days, January, March, May, July, August, October and December, are numbered 25 (Figure 4). The succession of the notches of varying depths around the periphery of the disc 16 corresponds to the succession of the months in the year.

A guide lever 26 (Figure 5), which is adapted to be rotatable in a vertical plane is provided with a locking-pin 27, which is arranged to cooperate with the notches in the month advancing wheel 16 in such a way that the guide lever 26 occupies a lower or higher position, according to the depth of the notch in which the locking pin 27 lies. The guide lever 26 is provided with a cam path 28, which lies partly outside the circumference of the month advancing wheel 16, for the pin 15, the purpose of which will be described hereinafter.

The year advancing wheel 17, which is arranged co-axially with the month advancing wheel 16 and the day advancing wheel is firmly seated on a sleeve 29, which is loosely mounted on the sleeve 21, connected with the month advancing wheel, so that it can rotate independently of the sleeve 21. The sleeve 29 supports a year disc 30 (Figure 1) having the numbers of successive years around its periphery. On the year advancing wheel 17, each fourth notch of the twelve notches provided therein is less deep than the others. These shallower notches are indicated by reference numeral 31 and correspond to the leap-years, the others, which are all equal in depth, are indicated by reference numeral 32 and correspond to the normal years. With the notches 31, 32 in the year advancing wheel 17 a guide lever 33 cooperates, which is adapted to be rotated in a vertical plane (Figures 1-3) the guide lever 33 being provided with a locking pin 34 and constructed similarly to the guide lever 26 corresponding to the month advancing wheel 16. The locking pin 34 on the guide lever 33 is adapted to cooperate with the notches in the year advancing wheel 17 in such a way that the guide lever can occupy two different positions, namely, the higher one when the locking pin 34 rests in one of the notches 31, and the lower when the pin rests in one of the notches 32. The guide lever 33 is also provided with a cam path 35 (Figures 2 and 3), which lies partly outside the circumference of the year ad-

vancing wheel, onto which path the pin 15 can slide, when the locking-pin 34 of the guide-lever 33 catches in one of the shallower notches 31 in the year advancing wheel 17, corresponding to the leap years.

As may be seen from Figure 1, the pin 15 is sufficiently long to enable it to advance the year advancing wheel also, when this is to be advanced. When the driving member 2 is in its normal position (Figure 3), the pin 12 on the driving member 2 engages in the notches 36 or 37 in the guide levers 26 and 33, in order to lock the latter in the position in which the pin 27 or 34 seated thereon engages with the month or year advancing wheel respectively.

When the clock mechanism operates, the pin secured to the hour wheel thereof comes into contact once daily with the projection 3 of the driving member 2, so that this latter is oscillated out of the position illustrated in Figure 3, and the pawl member 4 engages with the day advancing wheel 5, so as to advance it by one tooth or step. After each such oscillation, the driving member 2 is returned to its initial position by the spring 6. Each time the driving member 2 is rotated in the manner just described in order to advance the day-advancing wheel 5 one step, the pin 15 slides first on the cam-path 28 of the lever 26 and then on the cam-path 18 of the deflecting lever 19, without being able to come into contact with the month-advancing wheel 16, repeating this motion upon each movement of the driving member 2, until the pin 20 of the day-advancing wheel 5, towards the end of the month, engages the underside 19' of the lever 19 and gradually raises the lever 19 upwards into the position shown in Figure 2, so that the pin 15 now slides upon the last advancing stroke in the waning month between the cam-path 28 and the lever 19 and engages with the month-advancing wheel 16, so as to advance it one step.

The altitude of the cam-path 28 thus determines the moment when the pin 15 can come under the rising deflecting lever 19, in order to engage with the month-advancing wheel. When the locking-pin 27 of the guide-lever 26 rests in the deep notch 23 in the month-advancing wheel 16, corresponding to the month of February, the cam-path 28 of the lever 26 is so low that the pin 20 of the day-advancing wheel has to raise the control-lever 19 a comparatively small amount only, in order to permit the pin 15 to pass between the cam-path 28 and the deflecting-lever 19, so that the pin 15 can then reach the month-advancing wheel 16 earlier (when the day-advancing wheel has rotated through twenty-eight steps). But if the locking-pin 27 of the lever 26 rests in one of the notches 24 in the month-advancing wheel, the cam-path 28 is so high that the day-advancing wheel 5 must advance two notches or teeth further,

in order that the lever 19 may be carried upwards by the pin 20 to such an extent that the pin 15 can pass between the cam-path 28 and the lever 19. When the locking-pin 27 of the lever 26 rests in one of the shallower notches 25 in the month-advancing wheel 16, the cam-path 28 is at such a height that the day-advancing wheel 5 must be rotated one notch or tooth further, in order that the pin 15 may pass between the cam-path 28 and the lever 19. This postponement of the moment at which the advancing-pin 15 comes under the deflecting-lever 19, which otherwise prevents its engagement with the month-advancing wheel 16, causes the contact-edge 14' of the finger 14 to come into contact sooner or later with the pin 20 of the day-advancing wheel 5.

If, for example, the locking-pin 27 of the lever 26 rests in the deep notch 23 in the month-advancing wheel 16, corresponding to the month of February, the advancing-finger 14 comes, towards the end of the month, comparatively early into engagement with the pin 20 and then advances the day-advancing wheel 5, which is now at the 28th day of the month for the first time, four steps in one operation upon the deflection of the driving member 2, that is to say, as the notch 23 corresponds to the month of February, which usually has twenty-eight days, from the 28th February to the 1st March, whilst at the same time the pin 15 of the finger 14 advances the month-advancing wheel 16 by one step. Conditions are similar when the locking-pin 27 rests in the notches 24 in the month-advancing wheel 16 corresponding to the months with thirty days, but the finger 14 now advances the day-advancing wheel 5, which until the end of the month was advanced by the advancing-catch 4 tooth by tooth, by two teeth at the last stroke, whilst the alteration of the month is simultaneously effected. If such an extra advancement of the day-advancing wheel 5, which has altogether thirty-one teeth or advancing-degrees, were not to take place, the day-advancing wheel 5, which would be advanced one degree at a time, would be out of agreement with the month-advancing wheel 16 when the latter is adjusted to another month.

As soon as the month-advancing wheel 16 has been advanced one step by the pin 15, the lever 19 falls back for the time being into its deflecting position, in which it prevents the pin 15, which moves with the driving member 2 when the day-advancing wheel 5 is advanced, from coming into contact with the month-advancing wheel, until this is to be adjusted to the next month.

As may be seen from the drawings, the year-advancing wheel 17 is so much smaller than the month-advancing wheel 16 that the pin 15, although it reaches as far as to the year-advancing wheel, can only engage therein

when the pin 15 is in the deepest notch 23 in the month-advancing wheel 16. In Figure 2 the pin 15 is shown in engagement with the said notch 23, and the corresponding numbers on the discs 9, 22 and 30 are "31—12—29," that is to say, corresponding to the last day of the year 1929. The adjustment of the year-advancing wheel has now to take place. When the pin 15 engages in the notch 23 in the month-advancing wheel 16, it also comes into engagement with the year-advancing wheel, so that this is then advanced one step together with the month advancing wheel.

In leap-years, the locking-pin 34 of the lever 33 rests in one of the shallower notches 31 in the year-advancing wheel 17, the lever 33 and the cam-path 35 thereon occupying such a high position that, when the pin 27 of the lever 26 rests in the deepest notch 23 in the month-advancing wheel 16, corresponding to the month of February, and the lever 26 with the cam path 28 consequently occupies its lowest position, the cam path 35 of the lever 33, relatively to the cam path 28 of the lever 26, lies as much higher as corresponds to an extra advancement of one day of the wheel 5 in the advancement period at the end of a month. The pin 15 is thus led on the cam path 35 instead of on the cam path 28, and the day-advancing wheel 5 must then be rotated one more notch or tooth than is the case in a month of February with twenty-eight days, so that the lever 19 must be raised so high that the pin 15 can pass between the cam path 35 and the lever 19.

Consequently, the advancing pin 14 with its contact edge 14' comes into contact with the pin 20 of the day advancing wheel 5 one step later than in a month of February with twenty-eight days, and the day advancing wheel 5 is advanced only three steps or teeth instead of four, as previously described, while the month advancing wheel 16 of course is also advanced one notch again by the pin 15. The adjustment of the month advancing wheel to the 1st March is thereby postponed from the 28th February to the 29th February.

When the pin 34 of the lever 33 rests in one of the nine deep notches 32 in the year advancing wheel 17, the cam path 35 of this lever is so low that it has no influence on the month adjusting means.

In the constructional form illustrated in the drawings, the day, month and year advancing wheels are operatively connected with drum-shaped discs, which are provided with numbers corresponding to days, months and years respectively on the cylindrical peripheries. If these numbers are formed similarly to printing-type and combined with a pressing surface, a date-stamp is formed. The day, month and year discs may however be flat, and be provided on the outer circular portion of their surfaces with the said numbers.

The constructional form herein described and illustrated may, of course, be varied in many respects without exceeding the scope of the invention. For example, instead of the advancing pin 15 itself sliding on the cam paths 28 and 18, it could be operatively connected to a member specially provided for this purpose. Again, the cam paths 28 and 35 need not be jointed to the levers 26 and 33 themselves, as will be evident, but may be provided on separate discs, which may if desired be adjustably secured to the levers 26 and 33.

Having now described my invention, what I claim as new and desire to secure by Letters Patent is:

1. Date indicating apparatus comprising rotatable and independent day, month and year advancing wheels and a driving member, which is so arranged in relation to the said wheels that it advances the day advancing wheel one step daily, adjusts the month advancing wheel to a new month at the end of a month and also adjusts the year advancing wheel to a new year at the end of a year, the month advancing wheel being provided with twelve notches corresponding to the months in a year, the depth of each notch corresponding to the number of days in the month, characterized by that an advancing pin, which is operatively connected with the said driving member and serves to advance the month advancing wheel, is controlled by a deflecting lever extending in front of the month advancing wheel, and by a cam path, which is adjusted in height according to the depth of the notches in the month advancing wheel, in such a manner that, when the day advancing wheel is advanced by the driving member, the advancing pin is prevented, by the deflecting lever, from engaging with the month advancing wheel until towards the end of the month, and only towards the end of the month, when a pin provided on the day advancing wheel moves the deflecting lever, according to the adjustment of the cam path serving as a guide for the advancing pin, is the latter permitted to pass sooner or later under the deflecting lever so as to come into engagement with the month advancing wheel.

2. Date indicating apparatus as claimed in claim 1, in which the advancing pin is mounted on a finger connected to the driving member and provided with a contact edge which by means of the advancing pin led on the cam path, towards the end of a month, according to the adjustment of the cam path, is permitted to come into contact with the pin on the day advancing wheel which serves to move the deflecting lever, in order to advance the day advancing wheel in one operation on to the first day of the next month, in the case where on this wheel fewer advanc-

ing operations were effected than correspond to its division.

3. Date indicating apparatus as claimed in claim 1, in which the advancing pin serves to advance the month advancing wheel, and at the same time serves as advancing member for the year advancing wheel arranged coaxially with the month advancing wheel, the year advancing wheel having a diameter so much smaller than that of the month advancing wheel that the advancing pin, although it reaches to the year advancing wheel, can only come into engagement therewith when it is in the deepest notch in the month advancing wheel.

4. Date indicating apparatus as claimed in claim 1, in which with the cam path another cam path, which is adjustable independently thereof, is associated, which, in the case of a leap year, serves to guide the advancing pin, and then leads it, in the correct manner for advancing the year advancing wheel in a leap year, into engagement with the said year advancing wheel.

5. Date indicating apparatus as claimed in claim 1, in which the cam paths are provided on guide levers, which are rotatable independently of one another, and the position of which is determined by the month advancing wheel and the year advancing wheel, by means of the notches provided therein.

In witness whereof I have hereunto signed my name.

NILS OSKAR WILLINDER.
